COATED CONTAINER AND METHOD OF
PACKING, STORING, AND SHIPPING LIQ-
UIDS THEREINLloyd D. Benedict, Chicago, Ill., assignor to John
L. Bennett, Decatur, Ill.

Application January 23, 1932, Serial No. 588,271

2 Claims. (Cl. 99—181)

This invention relates to improvements in containers and in the art or method of packing, storing, shipping, and dispensing liquids in and from closed containers therefor.

5 The principal object of this invention is the provision of a container and process by which such container may be filled with liquid and the filled container stored and shipped, and the liquid dispensed from such container, the container being provided with a lining which will have an aging effect on the liquid in the container, will improve its quality and flavor, and will tend to prevent deterioration or spoilage of the liquid contents of the container.

10 15 For carrying out my invention, I provide a leak-proof container or package of suitable material, the container or package being coated or lined on the inside with a bituminous or resinous layer having embedded therein particles of wood or wood-like material which will have an aging or 20 maturing effect upon the liquid in the container and will improve the quality thereof. When the liquid has been placed in the container or package, the container or package may be stored for 25 an extended period of time and may also be shipped and delivered in the original container or package without having any deterioration or spoilage of the liquid in the container.

25 The container or package may be made of any 30 one of a number of various materials, as, for example, metal, including tin, tinned metal, sheet iron or steel, or other suitable metals. The container or package is provided with a lining which has the effect of improving the quality of the contained liquid and of preventing the deterioration 35 or spoilage thereof. For certain liquids, the interior of the container or package is provided with an adhesive coating or lining which contains small particles of a wood or woody substance, the wood particles being exposed and 40 adapted to be contacted by the liquid in the container. The container or package may be made in its final form and then provided with the lining, above described, or the sheet material 45 before being made into a container may be treated with a coating of the adhesive material containing the wood or wood-like particles. It is within the contemplation of my invention to use fatty acid pitches, rosin, resins, synthetic 50 resins or gums, tars, Brewer's pitch, other pitches, or similar adhesive materials or combinations thereof. The above-mentioned materials are adapted to coat the interior of the container, so as to prevent the liquid from coming into contact with the container, and also act as adhesives 55

to hold the particles of wood or woody substances.

As a specific example of the lining material which I may use, I have found that a pitch which is a residue from the distillation of cocoanut oil fatty acids is especially adapted for use with my invention. The distillation of the fatty acids is stopped at a point where the dropping point of the pitch is 30° C. While I have given this specific example, it is expressly understood that I am not limited thereto, but may use any 10 of the other above mentioned thermoplastic materials. In choosing the bituminous or resinous lining, it is essential that the tar, pitch, resin, or adhesive material selected will not impart a bad taste or odor to the liquid in the container, 15 and also shall be sufficiently flexible to permit the sheets of metal or other materials which are coated with it to be worked into the can or container without cracking or exposing any of the metal sheet surface.

20 I will now describe one form of carrying out my invention to provide a can or container with a lining as above set forth. The pitch or other similar material is applied to one surface of a flat piece of thin plate, or other sheet metal, and over this a coating of pitch is put and then a layer of granulated oak. The oak may be in the form of granulated particles, sawdust, or in any other similar form, so as to facilitate application to the pitch coating. The flat piece of metal 25 with its pitch coating and the oak granules spread uniformly over the top of the coating is then run into an oven on a moving conveyor, the oven being held at approximately 35° C. This permits the oak or woody particles to embed themselves 30 in the pitch, and as soon as this is accomplished, which should not be more than ten minutes, the sheet is removed from the oven and the excess granules removed by air pressure or any other convenient method. The sheet is then ready to 35 be made into cans. While I have mentioned oak as one of the woods which I may use, I do not want to limit myself in this respect, since other woods may be used. The invention is not restricted to an oven temperature of 35° C. given 40 in connection with one form of my invention, and it is to be expressly understood that this temperature may be varied due to different plant conditions, different atmospheric conditions, and different base materials.

45 50 55 Another method of applying the woody particles to the bituminous or resinous lining, includes placing the wood particles on the plastic coating of the sheet material and then rolling the wood particles into the plastic lining. Also

the wood particles may be sprayed by air pressure on to the coating on the sheet material or into the final container form so that the wood particles are forced into the lining and are caused 5 to adhere thereto. It is also within the contemplation of my invention to coat the inside of a finished container, and then coat this with my impregnating material or the adhesive and impregnating materials may be applied to the finished container in one operation.

10 The size of the particles or wood or woody material may be varied within relatively large limits. For different types of beverages, different types of wood or woody impregnating material 15 may be used. Instead of wood for certain purposes I may use multi-cel diatomaceous earth, or other porous material which has been previously impregnated with chemicals. On standing in contact with the liquid in the container 20 the liquid will extract the chemicals within the diatomaceous earth or other porous material.

It is, of course, essential that a sufficient amount of the wood or woody material in the lining or coating should be exposed to the liquid 25 in the can or container to bring about the aging or maturing effect. Instead of treating the sheet metal as above set forth, it is within the contemplation of my invention to form a plastic mass of bituminous or resinous material containing the wood or woody particles therein, the woody particles being present in sufficient number to be exposed so as to contact the liquid in the can or container for the purposes hereinbefore set forth.

30 35 During the aging process certain chemical reactions take place which modify the taste of the product. The lining assists such chemical reactions. The unfinished product may be put into the container and the necessary aging permitted 40 to proceed in the can itself while the can is being shipped so that the actual time of storage in the place of manufacture is shortened. The container or can made according to my invention may be used for beer or similar carbonated malt 45 beverages which require aging or maturing for producing the finished product.

In the practice of this process and in the use of my containers, the liquids may be packed in containers of suitable size and stored away for

a suitable length of time before being shipped. The aging and conditioning processes proceed even though the liquid is packed in these container units. The containers may then be shipped and the liquid dispensed from the container, or in the container as a unit, depending, of course, upon the size thereof and the demand therefor.

5 In the case of tin cans or metal containers, numerous special advantages are obvious:—In 10 filling there is a minimum amount of breakage of the containers and wastage of the liquid, the lightness in weight is an advantage in handling, storing, shipping and dispensing, and the exclusion of light from the contents thereof is also 15 advantageous. Also in filling there is no danger of the container breaking as when glass bottles are used. Furthermore, there is less breakage in shipping. The metal cans or containers also 20 protect the liquid from the deteriorating effect of the sunlight.

The drawing represents a vertical transverse cross section of a can or container showing an adhesive lining to which are attached particles of wood or woody material.

25 What I claim is:

1. The new beer-container and substitute for the glass beer bottle for packaging and delivering beer to the consumer, and which is a light-proof, gas-tight, non-fragile, metallic container 30 of the aforesaid character having a lining which separates the beer from the metal of the container and which comprises material of the group consisting of bituminous, tarry, pitchy and resinous materials, said lining also comprising exposed woody particles preservative of the quality of the beer.

2. Method of packaging beer as a substitute for bottling it, which comprises packaging the beer and maintaining its quality in individual 40 serving, non-fragile, light-proof, gas-tight metal cans in contact with a lining on the inside of said cans comprising material of the group consisting of bituminous, tarry, pitchy and resinous materials, said lining also comprising exposed 45 woody particles preservative of the quality of beer.

25 30 35 40 45 LLOYD D. BENEDICT.
